TABLE MAT OR PAD

Oscar Winter, Philadelphia, Pa.

Application March 11, 1929, Serial No. 346,193

9 Claims. (Cl. 45—68.4)

The improvements relate, first, to the hinges of a folding pad or mat which connect the leaves of said mat or pad, or a section thereof, the hinge between two leaves being so fashioned that the leaves will not become loose; secondly, to the provision of a flap or edge of a covering to lap over the edge of a table, or to lap over the edge of an adjacent section of a pad; and, thirdly, to the construction of a mat or pad, or a section thereof, so that the opposite surfaces will each be smooth and level, and the leaves maintain their proper shapes and relative positions under all conditions of service and after long use.

The invention consists in certain novelties of construction and in the combinations of parts as herein set forth.

The accompanying drawing illustrates a mat or pad embodying the improvements, the same being constructed and the parts combined according to the best mode or modes of procedure I have so far devised for the purpose.

Figure 1 is a top view of two folding sections of a mat or pad placed edge to edge to cover the top of the table, a flap in this instance overlapping the adjacent edges of the two sections.

Figure 2 is an enlarged section of Figure 1 on line 2—2.

Figure 3 is an enlarged section, on line 3—3 Figure 1, showing one of the hinges.

Figure 4 shows the hinge detached from the mat or pad.

Figure 5 illustrates a section of one of the coverings, the top one of oilcloth or the like in this instance with a strip of fabric stitched to the under surface thereof near the flap, or edge of the covering.

Each leaf of the folding mat, or section of the mat, comprises two sheets of soft, yielding, non-heat conducting material, as wool felt, 1 and 2, preferably secured together at their surfaces; and a stiff piece of cardboard 3 secured to the adjacent sheet by adhesive material, the said cardboard maintaining the lower soft sheets in their proper relative positions. The leaves have a common cover 4 provided with a flap or flaps 5 for the entire mat, or section, of oilcloth or the like; and a common covering 6 of cloth or similar ornamental fabric.

The hinge proper for uniting two sections or parts of the mat or pad at their adjacent edges comprises two strips of very strong fabric 7 and 8 united longitudinally inside their outer edges by a row of thread stitches 9, thus forming four leaves radiating from a common longitudinal axis coinciding with the row of stitches. The

edges of the strip 7, or two leaves, are firmly secured by adhesive material to the top edge surfaces of two adjacent sheets of the cardboard so that the line of stitches or the bending line is in or near the top surfaces of the two sheets of cardboard. The bent downwardly parts of the strip 8, that is, the bent downwardly parts of the other two leaves, are glued to the adjacent vertical edges of the cardboard sheets and to the vertical edges of the sheets 1 and 2; then the extreme edges are turned outwardly and lapped over the surfaces of adjacent sheets 1 and fixedly glued in position. The interior parts of two sections are thus hinged together at their edges. The drawing shows three interior parts united by two hinges.

Outside these interior parts the coverings are applied as follows:

The sheet 2 about its exterior edge is reduced in thickness by removing part of the material thereof, or the whole of it, to provide an open space 10 adjacent the edge of the cardboard. The covering 6 is applied to the lower surface of the leaves by forcing U-shaped folds 11, in the body thereof up between the adjacent edges of two leaves and securely securing them in position by adhesive material, as glue. The free edges are then drawn taut and bent over and inserted within the open space 10 and firmly secured in position by adhesive material. The entire surface of covering 6 may be secured to the under surface of sheet 1, if desired, so there will be no possibility of folds or wrinkles developing therein by long service.

The top covering 4 has strips of flexible fabric 12 secured to the under surface thereof by stitches 13 so as to provide a free edge or edges. When the top cover is applied to the three leaves this free edge or edges of strip 12 is turned under the edge of the cardboard sheet into the space 10 and firmly secured in position by glue or other adhesive material. The entire under surface of the top cover 4 may be secured to the top surfaces of the three sheets of cardboard so no folds or wrinkles can develop.

In the present example the flap 5 of the top cover extends around all sides of the three leaves, and the portion 14 thereof may lap over the edge of an adjacent section to close any space between the two sections, as shown at the right in Figure 2.

From the foregoing description it will be clear that I have provided a superior folding mat or pad which will preserve its original shape under all conditions of service. The hinge is very strong

and out of sight and in this instance not connected to the top covering. The top pasteboard sheet holds the other softer, yielding sheets in place. The yielding edges of adjacent sheets 1 and 2 hold the surfaces of the U-shaped folds in contact so there is no open space between them when the mat is unfolded. The open space 10 at the edge of the mat allows the insertion of the turned-over edges of the lower covering and strip 12 without increasing the thickness of the mat at its edge.

The flap 5 laps over the edge of the table, and when the tablecloth is spread over the mat its contact with the flap aids in holding the mat or 15 sections in place.

While I have shown a mat with three leaf sections and the leaves foldable one on another, the section may be constructed so one leaf will fold over and the other under the central leaf. Also 20 the mat or section may have one hinge only or a plurality of hinges.

What I claim is:

1. The combination in a foldable mat or pad and with the adjacent edges of two of its interior constituent parts, of a covering, and a hinge comprising two strips of flexible material, one strip disposed beneath the covering at the meeting edges of said parts and overlapping said edges and secured to the surfaces adjacent said edges, 25 and the other strip bent to form a U-shaped fold with free edges, said U-shaped fold being located between the adjacent vertical edge surfaces of said parts and secured thereto, and the two free edges of the strip secured to the said constituent 30 parts, one edge to each part.

2. A foldable mat having a plurality of sections two of which are united by a hinge, said hinge comprising two strips of flexible material united longitudinally inside their outer edges by 40 a row of stitches forming four leaves, two of said leaves lying throughout their areas in the same plane and being secured to the outer surfaces of the two sections, and the other two leaves being bent from the plane of the first mentioned two 45 leaves and their free edges secured to the opposite outer surfaces of the two sections; and a fabric covering having a U-shaped fold located between two of said leaves forming part of the hinge.

50 3. The combination in a folding mat and with the adjacent edges of two of its constituent interior parts, of a hinge comprising connected leaves of flexible material with a common longitudinal axis, two of said leaves being secured to the opposite edge surfaces of the two said parts and lying substantially in the same plane throughout their areas, and the other two leaves bent to engage the vertical edge surfaces of said 55 two parts, and their extreme edges turned outwardly; and two coverings one of which has a

U-shaped fold located between the bent portions of the two last mentioned leaves which engage the vertical edge surfaces of said two parts.

4. The combination in a folding mat and with the adjacent edges of two of its constituent parts, 5 of two coverings and a hinge comprising connected leaves of flexible material radiating from a common longitudinal axis, two of said leaves lying in the same plane and being secured to the adjacent outer edge surfaces of said constituent parts, and another leaf bent away from the common longitudinal axis engaging the vertical edge of one of said parts and its extreme edge turned outwardly and secured to one of said constituent parts; one of said coverings being provided with 10 a U-shaped fold which is located between the vertical edges of the said two parts.

5. A covering for a table mat having a strip or strips of fabric, as 12, secured to its under surface adjacent to the edge of the covering, said strip 20 or strips being adapted to secure the covering to the body of the pad.

6. A covering for a table pad having a strip of fabric secured to its under surface inside the outer edge of the covering leaving an extended 25 edge of the covering to lap over the edge of an adjacent section of a mat, said strip being secured to the body of the mat.

7. The combination in a foldable table pad, and with the adjacent edges of two of its constituent interior parts, of a hinge comprising four leaves of flexible material united substantially along a common longitudinal axis, two of said leaves being secured to the adjacent edge outer surfaces of said two interior parts and in 30 the same plane when the pad is unfolded so the bending line of the hinge will lie substantially at said plane, and the other two leaves bent downwardly from said common longitudinal axis to positions between the adjacent vertical edges of 40 said two constituent interior parts and their free edges turned outwardly in opposite directions and secured each to a separate constituent interior part, and two coverings, one applied to each of the outer surfaces of the united and hinged constituent interior parts.

8. The subject-matter of claim 7 wherein a fold formed in the material of one of said coverings is located between the adjacent vertical edges of the two interior constituent parts when the 50 pad is unfolded and removably secured in position, whereby a new covering may be substituted for one worn or soiled at either surface of the pad without interfering with the hinge.

9. The subject-matter of claim 7 wherein said hinge consists of two strips of flexible material united longitudinally inside their outer edges by 55 a row of thread stitches and forming four leaves.

OSCAR WINTER.
